[57] CLAIM

The ornamental design for a combined key chain and measuring tape, as shown and described.

DESCRIPTION

FIG. 1 is a top, front and left side perspective view of a combined key chain and measuring tape showing our new design.

FIG. 2 is a rear elevational view.

FIG. 3 is a right side elevational view.

FIG. 4 is a bottom plan view; and

FIG. 5 is a right side, rear, and bottom plan perspective view thereof, with the measuring tape extended.
